Patent No. 1,973,108, issued Sept. 11, 1934, to Bernard Rous, Brooklyn, N. Y., for an improvement in holders for fragile articles.

UNITED STATES PATENT OFFICE

1,973,108

HOLDER FOR FRAGILE ARTICLES

Bernard Rous, Brooklyn, N. Y.

Application June 14, 1932, Serial No. 617,093

3 Claims. (Cl. 229—6)

This invention relates to a holder for fragile articles.

The organization of the invention comprises a holder adapted to coact with a carton.

5 The object of the invention is the production of a holder, in which radio tubes, electric incandescent lamps, and various other fragile articles can be securely packed.

The third object of the invention is the production of a holder, in which a fragile article can be securely positioned without the coaction of a carton in which the holder may be inserted.

The fourth object of the invention is the production of a holder for fragile articles, which latter are visible when positioned in the holder.

The fifth object of the invention is the production of a holder for fragile articles, which latter can be tested after being inserted in the holders.

The sixth object of the invention is the production of a holder for fragile articles in which articles can be inserted without injury to the latter.

The seventh object of the invention is the production of a holder, in which cylindrical and spherical shaped articles can be securely held in directions longitudinal of said objects as well as laterally thereto.

In the accompanying drawing Fig. 1 represents a side elevation of an exemplification of the improved holder with a radio tube in place and a partial section of its carton as on the line 1, 1 of Fig. 4; Fig. 2 shows a section of Fig. 4 on the line 2, 2; Fig. 3 indicates a section of Fig. 4 on the line 1, 1; Fig. 4 represents a section of Fig. 1 on the line 4, 4; Fig. 5 shows a section of Fig. 1 on the line 5, 5 with the radio tube removed; Fig. 6 indicates a section of Fig. 1 on the line 6, 6 with the radio tube removed; Fig. 7 indicates a top view of Fig. 2; Fig. 8 is a partial portion of Fig. 3 with a modification, and Fig. 9 is a fragmentary portion of Fig. 3 with a further modification.

A carton 15 preferably of card board is shown with the front wall 16, the rear wall 17 and the side walls 18. The upper end of the carton is shown at 19 and its lower end is shown at 20. From each of the top and bottom ends of the wall 16 extend the outer flap 22 having the projecting leg 23.

50 Inner flaps 24 and 25 extend from the ends of the side walls 18. The corners of the carton 15 are shown at 26.

Referring to Figs. 1 to 7 the holder is designated in its entirety by the numeral 30 and is preferable made of moulded paper pulp, although

other material may be used. Corrugated paper may be used.

The holder 30 comprises the oppositely positioned longitudinal cylindrically bulged walls 35, that have the spherically bulged upper portions 36. The walls 35 converge from their upper to their lower ends. The said lower ends join with the pair of oppositely positioned cylindrical tubular portions 37, which are parallel to the longitudinal axis of the holder. By this disposition of said walls they are adapted to securely hug an object, in this instance the radio tube 38 having the socket end 38a with the contact pins 39. The walls 35 are indicated with the upper edges 44. The tubular portions 37 at their lower ends join with the pair of diverging supporting legs 45. Longitudinal edges of the walls 35 are indicated at 46. It will be noted that the walls 35 and their portions 37 are oppositely positioned and spaced from each other, so that the radio tube 38 and its socket end 38a can be seen when in position between said walls 35 and portions 37.

Pairs of longitudinal side wings 50 having the straight longitudinal outer edges 51, diverge from the edges 46 and extend to the corners 26 of the carton 15. Notches 52 are indicated in the edges 51 of the wings 50 for the support of a rubber band 53, string or other clamping means. Upper wings 56 diverge from the edges 44 and extend to the corners 26 at the upper ends of the carton. Curved supporting feet 58 are integral with the lower portions of the supporting legs 45. The feet 58 extend to the corners 26 of the carton 15 at its lower end. A table 60 is indicated with the square opening 61 and is spaced from the lower end of the carton 15. Table diverging supporting legs 62 extend from the table 60 and join with the feet 58. A second pair of table diverging supporting legs 63 also extend from table 60 to the lower end of the carton 15 and join with the legs 62. The lower face of the socket end 38a of the radio tube 38 bears on the supporting table 60 and the contact pins 39 extend through the opening 61.

The radio tube is positioned in the holder 30 with the walls 35 hugging the bulb of said radio tube 38, the spherical portions 36 bearing against the crown of the tube and the tubular portions 37 bearing against the socket end 38a. The operator positions the rubber band 53 in the notches 52 to maintain the walls 35 in position.

Referring to Fig. 8 only a fragmentary portion of the holder 30 is shown with the legs 45, the feet 58, the legs 62 and the table 65 similar to 60. The

latter in this modification has the cylindrical opening 66.

A fragmentary portion of an incandescent electric lamp is indicated at 70, having the threaded socket end 71. The latter extends through the 5 socket end 71. The latter extends through the opening 66.

Referring to Fig. 9 the carton is shown with its side walls 18, and its flaps 22, 24, and 25. The socket end of the radio tube is indicated at 38a 10 with its contact pins 39. The tubular cylindrical portions 37 of the walls 35 as well as the wings 50 are indicated. Integral with the lower ends of the portions 37 are shown the supporting tables 85, which are at right-angles to the portions 37 15 and extend inwardly therefrom. A pair of curved diverging supporting legs 86 extend from the supporting tables 85 and have integral therewith at their lower ends the curved supporting feet 88. The feet 88 extend to the opposite corners 26 of 20 the carton at its lower end. The feet 88 are connected by the foot plate 90 having the opening 91. The socket end 38a of the radio tube is supported on the supporting tables 85.

Various modifications may be made in the invention and the present exemplification is to be 25 taken as illustrative and not limitative thereof.

Having described my invention what I desire to secure by Letters Patent and claim is:

1. A holder of the character described of one 30 piece of moulded paper pulp, comprising a pair of oppositely positioned longitudinal cylindrically bulged walls with spherically bulged upper portions, a supporting table having an opening be-

tween said walls at the lower portions thereof and supporting means for said table between it and said walls.

2. A holder of the character described comprising a pair of longitudinal bulged walls, longitudinal side wings having notches in their upper portions integral with said bulged walls, a supporting table below said walls with its vertical axis positioned between said walls, supporting means for said table between it and said walls and means supported in the notches of said wings to maintain said walls in operative positions. 80 85

3. A holder of the character described comprising a pair of longitudinal cylindrically bulged walls, spherical bulged upper portions integral with said walls, cylindrical tubular portions at the lower end of the walls and integral therewith, said bulged walls and tubular portions respectively oppositely positioned and spaced from one another, a pair of diverging supporting legs extending from the lower ends of said tubular portions, a pair of longitudinal side wings extending from the longitudinal edges of the bulged walls, the edges of the tubular portions and the edges of 100 said supporting legs, a supporting table between said supporting legs adjacent to the lower ends of said tubular portions, a pair of table diverging supporting legs extending from said table, feet connecting the said supporting legs and the table supporting legs and a second pair of table diverging supporting legs extending from said table. 105
